UNITED STATES PATENT OFFICE.

AUGUST HILPERT, OF HOBOKEN, NEW JERSEY.

METHOD OF INLAYING SHEETS OF CARD OR LEATHER BOARD OR LIKE MATERIAL.

SPECIFICATION forming part of Letters Patent No. 230,776, dated August 3, 1880.

Application filed June 15, 1880. (Model.)

To all whom it may concern:

Be it known that I, AUGUST HILPERT, of Hoboken, in the county of Hudson and State of New Jersey, have invented a new and Improved Method of Inlaying Sheets of Card or Leather Board or like Material, of which the following is a specification.

The object of my invention is to provide a new and improved method of inlaying card or leather board and like fibrous material, thereby producing novel and effective ornamental sheets which may be used for various purposes.

The invention consists in punching the desired design out of a sheet of card or leather board, thick paper, or like fibrous material and filling in the apertures thus produced with corresponding pieces of the same or some other suitable material pressed into said apertures.

In the accompanying drawings, Figure 1 shows a piece of card-board provided with the monogram \$ inlaid according to my improved method. Fig. 2 is a cross sectional elevation of the same on line xx , Fig. 1.

Any desired design, monogram-letter, figure, or ornament is stamped or punched out of a sheet of card-board, pasteboard, leather-board, thick and heavy paper, or any other suitable fibrous or like material, and the apertures thus formed are filled in with corresponding pieces of one or more colors punched out of a sheet of the same or like material and pressed into the said apertures, so that they spread and bulge, and are thus secured in the apertures, and are also held by means of cement, glue, or some other suitable adhesive material.

The desired ornament or design may be punched out in one piece, or it may be pro-

duced by punching out a series of smaller pieces, and then filling in these apertures in 40 the manner described above.

The filling-pieces may be punched out and filled in with different-colored material before being pressed into the aperture in the main sheet.

Linear or curved ornaments may be produced by punching long straight or curved slots into the board and filling them in in the manner described.

The sheets ornamented in the manner described are especially adapted for chair and bench bottoms and backs, for decorating walls and ceilings, and like purposes.

Having thus described my invention, I claim as new and desire to secure by Letters Patent—

1. As a new article of manufacture, a sheet of card-board, leather-board, thick paper, or like material inlaid with pieces of the same or like material, substantially as herein shown 60 and described.

2. The method of inlaying card-board, leather-board, or thick paper, substantially as herein shown and described, and consisting in punching the desired design out of the sheet 65 of leather-board, card-board, or thick paper, and pressing a correspondingly-shaped piece of the same or like material into the aperture under great pressure, so that the piece spreads and bulges, and is thus held in the aperture, 70 as set forth.

AUGUST HILPERT.
